UNITED STATES PATENT OFFICE.

ANDREW M. CHEESEMAN, OF MILLDALE, KENTUCKY.

ROOFING-TILE.

SPECIFICATION forming part of Letters Patent No. 511,506, dated December 26, 1893.

Application filed October 26, 1892. Serial No. 450,053. (No model.)

To all whom it may concern:

Be it known that I, ANDREW M. CHEESEMAN, of Milldale, in the county of Kenton and State of Kentucky, have invented a new and useful Improvement in Roofing-Tiles, of which the following is a full, clear, and exact description, reference being had to the accompanying drawings, forming part of this specification, in which—

10 Figure 1 is a top plan view of a series of conjoined tiles constructed in accordance with my invention. Figs. 2 and 3 are vertical longitudinal sections on the lines II—II and III—III of Fig. 1. Figs. 4 and 5 are vertical cross-sections on the lines IV—IV and V—V of Fig. 1 respectively.

Like symbols of reference indicate like parts in each figure.

In the drawings, A, A', represent the tiles, 20 which may be made of clay or other suitable material and are of flat trapezoidal shape, having on one side of the upper surface, extending longitudinally, a hollow semi-cylindrical or angular marginal overlap or wing 2, 25 and at the other margin two substantially parallel tapering ribs 3, 4. The outer rib 4 extends along the entire length of the tile, while the other rib 3 terminates at a point about opposite to the shoulder 9.

30 Near the upper end of each tile are holes 5, enabling its attachment to the roof, and adjacent thereto are shallow transverse surface-grooves 6. The overlap or wing 2 of each tile has its upper end portion reduced in diameter, as at 7, sufficiently to fit beneath the lower end portion of the wing of the tile next above it when set in position, said lower end portion being hollowed out to form a socket on the under side for that purpose. This 35 socket terminates in a square shoulder, and the remainder of the overlap or wing 2 is hollowed out with a longitudinal groove 8.

The strengthening ribs on the under side of the tile are extended into the groove on 45 the under side of the wing and part way across the same, so that they may abut against the outer side of the marginal flange of the laterally adjoining tile and that the hollowed out portion may overlap said flange 50 and fit upon the surface of the rib 3 and may thus cover the joint. As an alternative con-

struction, though not so desirable, the wing throughout its entire length may be hollowed for the outer part only of its width. The reduced portion 7 is joined to the wider portion of the overlap 2 by an externally beveled shoulder 9, which may, however, be made abrupt in its projection, and the positions of these shoulders may determine the extent of overlapping of the tiles when set on the roof. 60 On the under side of each tile are transverse strengthening ribs 10, 11, 12, 13. The rib 13 is made thin and narrow so that it may fit in the surface groove 6 before mentioned; and the rib 12 may project from the under surface of the tile a distance equal to the tile's body. The other two are successively less in their degree of projection, so that when the tile is laid down, these ribs shall form the supports on which the tile rests, and shall 65 give strength and stiffness to the tile, permitting it to be made of lighter material than would otherwise be possible.

When the tiles are set in position on the roof, series of tiles A, A', are laid side by 70 side, the overlap or wing 2 on each tile fitting over the ribs 3 and 4 at the margin of the next tile, the margin of the wing resting upon the inner rib 3, and the outer rib fitting against the inner side of the groove 8 under the wing, 75 as shown in Fig. 5. The next series of tiles A' is laid above the tiles A, the ribs 13 of the tiles A' fitting within the groove 6 of the tiles A, the enlarged portions or sockets of the grooves under the wings at the lower 80 parts of the tiles A' fitting over the reduced portions 7 at the upper ends of the wings of the tiles A, and the shoulders on the latter preferably abutting against the end of the wings on the tiles A'. The tiles as laid are 85 secured to the roof by nails passed through the holes 5, and as each series is laid it covers the nail-holes of the series below, while the joints are covered and closed by the fitting of the margins of the wings 2 on the 90 ribs 3, the fitting of the ribs 4 against the inner side of the groove 8, and the overlapping of the ends of the tiles. The trapezoidal shape of the tile, which is narrower at its lower portion, permits the lower end of the 95 body of each to lie between the upper end of the wing and the marginal rib 4 of the tile 100

next below it. This is effected without necessity for cutting the corners of the tiles.

The advantages of my invention will be appreciated by those skilled in the art. The tile is simple in construction and is strong, neat, and easily set in place.

Without limiting myself precisely to the form of the parts shown in the drawings, which within the limits of my claims may be varied by the skilled mechanic, I claim—

1. A roofing tile having along one edge a marginal overlap or wing of upwardly arched form, said wing having at one end a short reduced portion connected thereto by a shoulder arranged to act as a stop for and be covered by the next tile; substantially as described.

2. Roofing material comprising a tile with an arched overlap or wing, and an adjacent tile having an outer and an inner marginal rib, the outer rib fitting under the overlap, and the inner rib supporting the edge of the

overlap, and terminating short of the end of the tile; substantially as described.

3. A roofing tile having along one edge a marginal overlap or wing of upwardly arched form, said wing having at one end a reduced portion connected thereto by a shoulder, and a longitudinal tapered rib upon the tile terminating at substantially the same level as the shoulder and coacting therewith to form stops for the next tile; substantially as described.

4. A roofing tile having a marginal overlap or wing and near the other margin a longitudinal tapering rib arranged to support the wing of the next tile; substantially as described.

In testimony whereof I have hereunto set my hand this 17th day of October, A. D. 1892.

ANDREW M. CHEESEMAN.
